Hartnett, Murray.

UNITED STATES PATENT OFFICE.

ROBERT K. CLARK, OF WEST SPRINGFIELD, MASSACHUSETTS, ASSIGNEE TO THE AMERICAN THREAD COMPANY, OF JERSEY CITY, NEW JERSEY, A CORPORATION OF NEW JERSEY.

COTTON YARN AND METHOD OF PRODUCING THE SAME.

1,254,000.

Specification of Letters Patent. Patented Jan. 15, 1918.

Original application filed April 4, 1917, Serial No. 159,655. Divided and this application filed June 21, 1917. Serial No. 175,983.

To all whom it may concern:

Be it known that I, ROBERT K. CLARK, a citizen of the United States, residing at West Springfield, county of Hampden, 5 State of Massachusetts, have invented a certain new and useful Improvement in Cotton Yarn and Methods of Producing the Same, of which the following is a full, clear, and exact description.

10 My invention relates to a new and improved cotton yarn and has for its object to provide a cotton yarn having a twisted core with a flocculent exterior adhering thereto capable of being used in the production of 15 thick and fluffy fabrics, sweaters and the like, of a warm and soft nature, in which the interstices of the fabric when loosely knit or woven shall be largely filled up with a flocculent material adhering to the surface 20 of the yarn and a method of producing the same. Cotton yarn of such nature may be described as "fluffed yarn," and the action by which it is produced may be called "fluffing," by which I mean the partial combing 25 out of enough of the fibers of a strand of yarn to produce a continuous flocculent surface thereon, which is secured thereto. I believe such fluffed yarn, as well as the apparatus and method which I have devised 30 for producing it, to be novel with me.

The following is a description of my invention, reference being had to the accompanying drawings, which show apparatus embodying mechanical features suitable for 35 producing my yarn and also show my cotton yarn produced thereby. In these drawings,

Figure 1 shows a section of yarn;

Fig. 2 is a plan view of a machine embodying apparatus for producing my yarn;

Fig. 3 is a longitudinal section of the same.

Referring more particularly to the drawings, Fig. 1 shows a length of yarn embodying my invention, the same being composed of a loosely twisted core 17, made up of a plurality of strands and having a fluffy and flocculent surface 18, comprising a multiplicity of fibers which have ends extending 45 into the strands of said twisted core, and free ends presenting a woolly external sur-

face. The outer ends of these external fibers are free while the inner ends extend into the strands of the twisted core so as to be intermingled with the fibers of the strands of 55 which the core is composed and secure the flocculent exterior to the core. In my cotton yarn produced as hereinafter described, the length of the exposed ends of the fibers constituting said flocculent surface may on the 60 average exceed twice the diameter of the core when the core does not exceed one-sixteenth of an inch.

In the machine for producing it (Figs. 2 and 3), 1 is a frame carrying a creel 2 supporting a series of bobbins 3, having wound thereon loosely twisted yarn 4. This loosely twisted yarn is made up of a plurality of loosely twisted strands which are themselves loosely twisted together, the yarn 70 preferably being a two-ply yarn. Mounted upon the frame is a guide tension bar 5, beneath which the strands 4 of yarn pass to a grooved guide-bar 6, from which they pass to other guide bars 7 and 8, the latter being 75 also grooved, and to leather covered nip or pulling rollers 9 and 10 between which they pass. The nip rolls are power-driven by gearing from the shaft of an adjacent roller 12 reducing from about 5 to 1. The tension 80 bar 5 alines the various strands so that they thereafter lie in a common plane and creates enough tension to prevent irregularities of pull of the yarn coming off and spools being transmitted to the rest of the 85 machine. The guide-bars 6, 7 and 8 are shown in the form of rolls, which may be mounted so as to freely revolve. Between the bars 6 and 7 is a roller 11 covered with 90 projecting needles of springy tempered wire so as to have a fluffing or napping surface and between the bars 7 and 8 is a second similar fluffing roller 12, the two rollers being geared together by gears 13 and the shaft of one of them is provided with a pulley 14 which is driven by a belt from the motor 15. The wire teeth or needles of 95 these fluffing or napping rollers are preferably straight instead of bent as in ordinary card clothing and are substantially perpendicular to the surfaces of their rollers. 100 The fluffing rollers are substantially the

same as in regular gidding machines for finishing woven fabrics, except that I preferably make the needles straight. The roller 11, as shown in Fig. 3, operates clockwise, while the other roller 12 operates counter-clockwise, so that their movements are in opposite directions, the first roller turning toward the point from which the yarn passes and its movement thus being 5 against or in opposition to the movement of the yarn. The bars 6, 7 and 8 are vertically adjustable and are so adjusted that the strands of yarn passing over them are in proper engagement with the needle points 10 upon the fluffing rollers 11 and 12 to raise the fiber on the yarn exterior. The bar 7 positions the strands for the two rollers 11 and 12 and acts to prevent the yarn from getting slack and entangled in the needles. 15 The amount of flocculent material formed on the exterior of the yarn can be varied somewhat by changing the positions of the strands relatively to the needles by adjusting the bars 6, 7 and 8. The fluffing rollers 20 11 and 12 revolve at a relatively high rate of speed so that their peripheral surfaces move at about the rate of 1,000 feet a minute, while the yarn passes forward at the rate of about 75 feet a minute, due to the 25 corresponding peripheral speed of the nip rolls 9 and 10. The teeth upon the fluffing rollers engaging fibers upon the exterior of the strands partially free them from the twisted strands with the result that there is 30 produced upon the surface of the strands a flocculent exterior composed of a multiplicity of fibers, one end of each of which extends into and forms part of a strand of the twisted core, so as to be intermingled 35 with the fibers thereof, resulting in a product which is represented, as well as it can be, in Fig. 1. Each strand after this flocculent exterior has been produced thereon passes between the nip rollers 9 and 10 and is then 40 wound into cylinders or other suitable form by any suitable take-up mechanism 16, preferably a drum winder having a suitable traverse. The strands of yarn as they pass from the bar 6 are kept under a light tension 45 so as to prevent the strands from being caught upon the fluffing rollers. The action of the fluffing roller 11 increases this tension in the strands of yarn that have passed it, but should not stretch them so tightly as to 50 interfere with the fluffing needles getting hold of fibers on their exteriors and partially freeing the same from the twisted cores. The machine treats a multiplicity of strands at the same time, the strands being 55 kept parallel and treated independently as they pass between the bars 6 and 8.

In producing my yarn I supply a plurality of separate strands of loosely twisted multiple-ply yarn to the machine in the 60 manner above described and subject the

strands as they pass between the points on the bars 6 and 8, under the tension as above specified, to the fluffing action of rollers 11 and 12 so as to partially comb out and free enough of the fibers extending to the exterior of the untreated yarn to produce the desired flocculent result. I preferably cause the roller 11 first engaging the yarn to rotate in the direction of the point from which the yarn comes, *i. e.*, in opposition to the movement of the yarn, and the other roller 12 to rotate in the opposite direction. This results in a counter-balancing pull on the intervening portion of the yarn so that the pull necessary to draw the yarn through the machine is not seriously affected by the action of the fluffing rollers and a slack which may become entangled is not likely to be produced. This relation of peripheral rotation also accomplishes the result of raising the fibers in more than one direction, thus producing a more general fluffing. As the yarn passes between the two points 6 and 8, it revolves slightly on its own axis on account of the twist therein and the tension under which it is placed, and also on account of the action of the fluffing cylinders thereon, with the result that substantially all sides of the strands are subjected to the fluffing or napping action of the wire 95 needles so that the flocculent surface extends to all sides of the strand.

The yarn, after being treated in the manner above described, constitutes my new product shown in Fig. 1.

While I am aware that woven fabrics have been teazled by machinery, and a teazled product produced thereby, I am not aware that anyone has devised an apparatus for or process of teazeling unfabricated lengths of yarn, or produced a length of yarn having a continuous teazled surface consisting of fibers which were originally within a twisted strand, but have been pulled out so as to be, as in my product, 110 partially but not wholly detached.

This application is a division of my application Serial No. 159,655, filed April 4, 1917.

As will be evident to those skilled in the art, my invention permits of various modifications without departing from the spirit thereof or the scope of the appended claims.

What I claim is:

1. An extended length of cotton yarn, having a twisted multiple strand core of cotton and a flocculent surface, said surface comprising a multiplicity of cotton fibers presenting a continuous fluffy appearance and having ends extending into and forming part of the strands of said twisted core and intermingled with the fibers of the strands of which said core is composed.

2. An extended length of cotton yarn having a loosely twisted multiple strand

core of cotton and a flocculent surface continuous throughout the length of the core and comprising a multiplicity of cotton fibers having their inner ends extending 5 into and forming part of the strands of said twisted core and intermingled with the fibers of the strands of which said core is composed and their outer ends free.

3. The process of treating yarn, which 10 consists in passing an extended strand of yarn from one point to another and fluffing it continuously throughout its length as it passes between said two points so as to

loosen portions of its fibers and produce a continuous flocculent surface. 15

4. The process of treating yarn, which consists in passing an extended strand of yarn from one point to another and fluffing it continuously throughout its length in a direction opposed to the movement of the 20 yarn and also in the opposite direction as it passes between said two points so as to loosen portions of its exterior fibers and produce a continuous flocculent surface.

ROBERT K. CLARK.
